UNITED STATES PATENT OFFICE.

LOUIS SMITH, OF CHICAGO, ILLINOIS, ASSIGNOR OF ONE-HALF TO WILLIAM L. HALL,
OF CHICAGO, ILLINOIS.

METHOD OF AND APPARATUS FOR MAKING PRINTING PLATES.

Application filed August 4, 1921. Serial No. 489,710.

This invention relates to a novel method of producing printing elements, such as offset printing plates and lithograph printing plates and the like for printing in one or in different colors, and made from printing forms, such as plates, rules, types, or cuts, and to a novel machine or press for practicing the method.

The method herein shown is disclosed 10 in my prior U. S. Reissue Letters Patent No. 15,481, dated October 31, 1922, to which reference may be had for a general exposition of said method.

In accordance with my novel method of 15 making printing elements, such as offset, lithographic printing plates, and the like, from printing forms of the character described, I employ a printing form element, a proof element to prove and register the 20 printing forms, a printing plate element, and a transfer element, which latter rolls with its surface in contact with and picks up the impression from the proved and registered printing form element, and by 25 rolling movement of the transfer element carries or transfers the impressions to the printing plate element to produce, after subsequent known treatments of the plate, an offset or lithographic printing plate, and I 30 adjust one of said printing forms or printing elements relatively to the transfer element to enable the impressions of the printing form element to be duplicated or printed in predetermined relation on the final printing element; or the objects of the printing 35 form can, by suitable spaced arrangement of the printing forms, relatively to the transfer element, be made to be superimposed on the printing element or plate for producing 40 color printing elements or plates, or for producing superimposed impressions of the same color on the printing element or plate. Further, the said impressions, after they 45 have been picked up from the printing form element may, by the use of a secondary transfer element, be reversed and imprinted on the printing element, so that the impressions appear thereon in reverse way as on the printing form element; that is, if the 50 printing form element is negative the impressions delivered on the printing element by the secondary transfer element may be positive, and vice versa. Further, the printing element may be made to be moved relatively to the transfer element by which the

impressions are transferred to the printing element, so that the printing element can be made to receive impressions from the transfer element at different areas of the printing element and also a printing element longer than the transfer element can be made. 60

When beginning the method, the first printing form is proved and registered by a proving cylinder. It is locked preferably 65 at a corner of an adjustable bed and can constitute a key form by which other forms may be proved and registered. If the bed be a double bed and adapted to support two different kinds of objects with respect to 70 their lines which are to be printed on the ultimate printing element in superimposed relation, the printing forms will be locked on the bed at spaced intervals, relatively to the effective contact surfaces of the proof and 75 transfer elements, so that after a key form is proved and registered another printing form can, by its guidance, be proved and registered in such position that the impressions of both forms will appear in superimposed relation on the proof and transfer 80 elements and will, by the transfer element, be transferred in superposed relation on the printing element; and any practical number of such impressions may be superimposed. After the forms have once been 85 proved and registered, proper manipulation of the supporting bed for the forms and of the transfer elements over the forms enables the transfer elements to be filled throughout the entire or less than all of the area 90 thereof, both longitudinally and circumferentially, and the impressions so transferred may in one operation of the transfer element transfer all the impressions thereon 95 to the printing element, either directly, or through the cooperation of a secondary transfer element.

The machine embodying my invention follows the general construction of the machine illustrated in my aforesaid prior patent, the details of operating the transfer elements or cylinders with respect to their travel along the printing forms and plates, with respect to means for causing them to 100 travel out of contact with said forms, plates, and with respect to the means for reversing the impressions and the means to transfer the impression on plates longer than the transfer elements being broadly the same. 110

The improved method and machine will now be described in connection with one embodiment of the invention, but it will be understood that the invention is capable of 5 adaptation to other specific forms of mechanisms, and the method may be practiced in somewhat differently disposed steps. The invention is, therefore, not limited to the particular disclosure herein shown, except as 10 to claims wherein details of the disclosure are specifically set forth and as imposed by the prior art.

As shown in the drawings:

Figure 1 is a plan view of the proof end 15 of the press, with parts omitted.

Figure 2 is a plan view, showing the transfer end of the press, with parts omitted, which, combined with Figure 1, shows a plan view of the entire press.

20 Figure 3 is a side elevation of the proof end of the press.

Figure 4 is a section indicated on the line 4-4 of Figure 7.

25 Figure 5 is a side elevation of the transfer end of the press.

Figure 6 is a section indicated on the general line 6-6 of Figure 2.

Figure 7 is a transverse section on the line 7-7 of Figure 2.

30 Figure 8 is a side elevation of the proof roller, its mounting, and gears for operating it.

Figure 9 is a section on the line 9-9 of Figure 8.

35 Figure 10 is a section on the line 10-10 of Figure 9.

Figure 11 is a horizontal section on the line 11-11 of Figure 8.

40 The general contour and dimensions of the frame 15 of the machine may be of any suitable form to give support to the various elements and to the bearings for the cylinders hereinafter described. The frame is shown as embracing side members 16 connected by cross members 16', and legs 17.

45 Said frame supports a bed, designated as a whole by 18, for the printing forms A and also a bed 19 for printing elements B to be made, in a manner which will hereinafter 50 more fully appear, the said beds being spaced longitudinally of the frame. The printing element bed 19, which is disposed transversely of the frame 15, is longer than the width of the frame, and is supported to be shifted laterally relative to the length of the frame, for a purpose hereinafter to be described.

55 At this point it may be observed that said printing element bed 19 can be shifted transversely of the frame 15 on a transverse 60 tension frame 20 by pinions 24, 24, which are fixed to and driven by a shaft 25 that has bearings in members of the frame 20 which latter members are recessed to receive the bed 19. The shaft 25 has a hand wheel 28 65 by which to turn it to act through the pinions

24 and downwardly facing racks 29 on the underside of the printing element bed.

The bed 18 is an adjustable bed in that it is supported for adjustment both laterally and longitudinally of the frame and the 70 transfer cylinder or cylinders, as will hereinafter more fully appear, and in the general manner illustrated in my aforesaid United States patent. The bed receives and supports in any suitable manner chases 31 for the printing forms A. The said bed 18 is also a double bed, in that it is adapted to support two spaced printing forms in such relation relatively to a transfer element that impressions from both forms can be proved in superimposed relation by a proof cylinder and can be transferred in separate or superimposed relation on a transfer element, and by said transfer element be imprinted on a printing element to produce an offset or lithograph printing plate. Said bed is centrally divided by a transverse ridge or rail 32, and is supported on a carriage 35 of any suitable form that is adjustable longitudinally on the frame, and on which carriage and a lateral extension 36 thereof said bed is adapted to be adjusted laterally. Thus the lateral adjustment of the bed 18 on the carriage and the longitudinal adjustment of the carriage on the frame, carrying with it 95 said bed, imparts both lateral and longitudinal adjustment movements to the double part bed relatively to the main frame and the transfer and proof cylinders.

The means shown for shifting the bed 100 laterally on said carriage 35 comprises a threaded shaft 38 that is threaded through a nut 39 which is fixed to and depends from said bed. Said shaft has rotative bearing at 40 in the side carriage rail 41 but is axially fixed in its bearing. It is adapted to be operated by a hand wheel 42 at one side of the machine frame. The means shown for giving movement to the carriage longitudinally of the frame comprises a rotative shaft 43 that extends between, and has rotative bearings at 44 in, the side members 16 of the frame, and said shaft is provided with pinions 45 that mesh with the teeth of the downwardly facing racks 44' 110 on the side rails 41 of the carriage. Said shaft 43 is adapted to be rotated by a hand wheel 46. Suitably constructed and connected micrometer mechanisms 48, 49 can be connected, respectively, to the shafts 38 and 43 to determine accurate and delicate adjustments on the bed.

56 designates a proof cylinder that is adapted to normally occupy a space forwardly beyond the printing bed and is adapted to roll over and in proof contact with the printing forms supported on said bed, by means hereinafter to be described. 57 designates what may be termed primary and secondary transfer cylinders. The

transfer cylinders are so supported and can be manipulated in such a way that if the impressions are to be transferred from the printing forms to the printing element B, 5 one of said transfer cylinders is adapted to be rolled or otherwise shifted directly to the printing element or plate, and the transfer imprinted directly thereon. If the impressions of the printing forms are to be 10 reversed on the printing element B, the transfer cylinder 56, after being moved away from the printing forms, can be rotated in peripheral ink transfer contact with the cylinder 57, after which the latter cylinder 15 is rolled bodily over and in ink transference contact with the printing element or plate B.

All of the cylinders 55, 56, and 57 will be provided with the usual longitudinal clearance recesses (as indicated, for instance in 20 the dotted line in Figure 10) to receive the grippers for the proof paper and the blankets of the respective cylinders, and in the present construction of the press these recesses serve, in connection with stationary 25 or marking parts on the frame, as the end and central rails of the bed 18 and the marginal rails of the bed 18, and in cooperation with the cylinder driving means, as means to maintain the registry of the cylinders 30 relatively to the printing forms and the printing elements and also for bringing the cylinders 56, 57 in contact along the proper line for mutual transference of the impressions from one to the other when said cylinders are rolled in peripheral contact, as will 35 hereinafter appear.

Each of said cylinders is mounted to rotate on an axially disposed shaft 59, the shafts for all of the cylinders being marked 40 with a common reference character. Said shafts are supported, through rollers 60 on horizontal tracks 61, 61 at the sides of the frame, said tracks extending from one end to the other of said frame. The said tracks 45 61 are formed on a superframe, so to speak which is designed, in addition to its cylinder supporting function, to guide the cylinders in their travel across the printing forms and printing elements and to hold the cylinders 50 properly aligned.

Said superframe embraces lower rail-like members 63 at the sides of the frame and disposed parallel to the members 16, and upper, correspondingly located, guide rails 55 64, that are connected to the lower rails by end standards 65 at the ends of the frame.

The lower rails 63, in addition to carrying the upwardly facing track for the rollers 60, are formed to provide exterior thereto upwardly facing parallel racks 66 at the sides of the machine frame laterally exterior to the tracks 61. With said racks mesh pinions 67 that are fixed to the cylinder shafts 59 exterior to the supporting rollers 60 and 65 rails 61. The said cylinders are driven in-

directly through a gear train from the driving connection of said pinions 67 and racks 66 to the cylinders in such a way that the cylinders may be caused to be bodily moved over the printing forms and printing elements and rolled in transfer contact therewith, or by breaking said gear train said cylinders may be caused to move over said forms without rotational movement thereof. When the cylinders are thus moving without 70 rotating, the cylinders are out of contact with said forms and printing elements and this movement may occur at a time when the cylinder clearance recesses are at the bottoms of the cylinders and, therefore, out of contact with the lower, normally coactive surfaces. Other means may be employed to separate the cylinder surfaces from the printing forms and printing element surfaces, such, for instance, as the track elevating means shown in my aforesaid prior patent. 75 80

The said cylinder gear driving connections for the cylinders 56, 57 are also such that the drive connections to the rack can be 90 broken when the cylinders are brought into peripheral contact to transfer the impressions from the cylinder 56 to the cylinder 57. At this time the cylinders will be locked together and power can be transmitted to rotate both of the cylinders through direct power application to one cylinder, as will 95 hereinafter more fully appear.

The driving and rotating gear mechanism for all the cylinders are substantially the same and the description of one gear train and the means for manipulating the same will answer as a full description of all, the same reference letters being employed to denote like parts. 100

Each cylinder has at one end an internal annular rack or gear 70. 73, 74 designate what may be termed cross heads which are slidable along the rails 63, 64 of the superframe before referred to. The cross head 73 is associated with the proof cylinder actuating mechanism. Each cross head 73, 74 is of general fork shape. It has at its upper end guide collars 75 that are slidable on the rail 64. The fork arms comprise rather broad plates 76. One of said plates 76 of each cross head is provided at its lower end with a dovetail rib 78 that slides in a longitudinally disposed undercut groove 79 formed on the outer face of the adjacent lower rail 63. Said grooves and the rails 64 extend from end to end of the superframe. The said plates of each cross head are formed with registering openings to receive and support short shafts 83, 84 and the extended ends of the cylinder shaft 59. 110 115 120

Said fork arms are also pierced to form guide openings to receive a locking pin 86 that engages at its inner end an opening or openings 87 in the adjacent end of the cylinder. 125 130

der. An expansion spring 88 serves to normally hold the inner end of said locking pin engaged in the opening 87, so that the cylinder at times can be held from rotation on its shaft 59. When the locking pin is withdrawn against the action of the spring 88, it may be held in an unlocking position by an extension or lug 89 (Figure 11) which normally lies in a recess in the cross head, 10 and which is adapted, when the pin is withdrawn and rotated on its axis to engage an imperforate part of the cross head and thereby locked from shooting into cylinder locking position.

15 Between the arms of the head at the driving end of the cylinder and fixed to the shaft 83 is a pinion 90. To the inner end of said shaft 83, associated with the transfer cylinders, are fixed two pinions 93, 94, the latter 20 meshing with the internal gear or rack 70 at the adjacent end of the cylinder, and the former adapted for meshing engagement with gears for imparting movement of rotation to the cylinders 56, 57 when they are 25 adjusted to be rotated in ink transferring contact. In the driving mechanism for the proof cylinder no gear corresponding to the gear 93 will be employed, only a single pinion 94 on said proof cylinder being fixed 30 to the shaft 83.

The shaft 84 is mounted in bearing blocks 96 which have longitudinally sliding movement in slots 97 in the fork plates of the cross head. An idler pinion 99 is mounted 35 to rotate freely on said shaft 84 and it is adapted to be meshed with and demeshed from the pinions 67 and 90. When the pinion 99 is meshed with the pinions 67 and 90, the cylinder can be turned by the hand 40 crank 102 which may be fitted to the extended end of the shaft 59 or 83, and the pinion 67 on the shaft 59 operates through the idler pinion 99, the pinion 90, the shaft 83, and pinion 94 and internal gear 70, with the 45 function of both causing the cylinder to travel along the frame and to also cause the cylinder to turn on its axis, with its cylindric surface in ink transferring contact with the printing forms or plates. When the 50 pinion 99 is demeshed from the pinions 90 and 67, power to rotate the cylinder from the rack will be cut off, but the cylinder may be caused to be moved bodily along the frame through the action of the pinion 67 55 and rack 66.

The idler pinion 99 may be demeshed from and meshed with the pinions 90 and 67 through any suitable mechanism. As herein shown, this movement is effected by sliding the bearing block 96 in which the shaft for the idler pinion is mounted, as by means of a hand lever 105 that is pivoted at 106 to the cross frame, and is provided between its ends with a slot 107 in which operates a 65 lug 108 that extends outwardly from one of

said blocks 96. This swinging movement of the lever 105 forwardly or backwardly will give direct movement to the bearing blocks 96 and said idler pinion to mesh it with and demesh it from the pinions 90 and 67.

This arrangement is useful in connection with the transfer cylinders 56, 57, which are adapted in certain adjustments of the mechanism to be rotated in ink transferring contact with the type forms and plates, and to be unlocked from the rack driven gear at a time when the cylinders are brought into position for rotating the cylinders in ink transference contact with each other and to thereby transfer the impressions 80 picked up by the cylinder 56 and reverse them on the cylinder 57, to be by the latter cylinder transferred to the printing element reversely from that shown in the printing forms. A further advantage of thus breaking the cylinder rotating gear train is to permit the cylinders to be moved over the printing forms and printing elements at times when it is not desired to rotate them. In such case the cylinder is locked from rotation by the locking pin 86 or other suitable means, and the pinions 67 can be rotated by a crank applied to the squared, extended end of the cylinder shaft 59, so as to cause the pinions to be driven along the racks and to 95 carry the cylinder non-rotative.

Means are provided for positively rotating the cylinders 56, 57 in proper direction to transfer impressions from one to the other and for locking the cylinders to hold them in proper peripheral ink transferring contact. The means for thus rotating the cylinders, when the idler pinions are demeshed, embrace idler gears 112, 112, which are relatively mounted on stub shafts 113, one carried 100 by each of the cross heads, and which, when the two cylinders 56 and 57 are brought to the position shown in Figure 6 mesh with each other. Each gear 112 is mounted in its own cross head, so as to be constantly in mesh with its associated pinion 94. The length of travel of the cylinders bodily along the frame, relatively to their effective circumference is such that the clearance recesses of the cylinders will always be brought 105 into the relative position shown in Figure 6 when the cylinders are brought together for mutual impression transfer and rotation of said cylinders. The length of the peripheral travel of the cylinder 57 from the position 110 shown in Figure 6 to the point at which the cylinder blanket strikes the printing element B is such as to cause the blanket to properly strike the printing element when the cylinders are released, the idler gear 99 associated with the cylinder 57 is thrown into the driving train and the latter cylinder is rolled along its tracks, by driving engagement with the upwardly facing racks, towards said printing plate or element B. The cylinder 115

120 shown in Figure 6 to the point at which the cylinder blanket strikes the printing element B is such as to cause the blanket to properly strike the printing element when the cylinders are released, the idler gear 99 associated with the cylinder 57 is thrown into the driving train and the latter cylinder is rolled along its tracks, by driving engagement with the upwardly facing racks, towards said printing plate or element B. The cylinder 125 130

57 may be rolled forwardly over the printing element to permit its transfer or it may be moved forwardly over the bed while non-rotative and imprint its impression on the printing element or plates when moving rearwardly.

The means shown for holding or locking the cylinders 56 and 57 in operative relation during such rotative transfer contact is made 10 as follows:

115 designates a latch that is hingedly supported on the lower pivot end of the meshing and demeshing lever 105 associated with the cylinder 56 and is provided with a hook 116

15 that is adapted to engage over a pin 117 on the cross head associated with the cylinder 57.

Two latches 115 are provided, one at each end of the pair of cylinders. Said latches are loosely or pivotally connected between their

20 ends to upwardly extending links 119, which latter are connected at their upper ends to arms 120 that are fixed to a transverse rock shaft 121 which is rockingly mounted in standards 122 that rise from the guide sleeves

25 75 of the cross heads. The said rock shaft is provided at the driving ends of the cylinders 56, 57 with a hand lever 124 which, when the outer end is depressed, rocks the shaft 121 and lifts the hook 116 of the latch 115 away

30 from the pins 117, thereby freeing the latches from the pins 117 and permitting the cylinder 57 to be rotated away from the transfer position toward the printing element or plate B when its driving gear train

35 is again established. The weight of the parts may permit the latches to drop by gravity and be held against stop pins 126.

130 designates a set of inking rolls of any suitable form that is adapted to be connected with the proof cylinder to travel therewith.

The shafts of said inking rolls are rotatively mounted in triangular plates 131 pivoted by a cross rod 132 to rearward ex-

40 tensions 133 of the cross heads, said rod extending beyond the cylinder for bearing support in said rearward extension 133. The said set of inking rolls 130 are adapted to be raised and lowered independently of the inking contact of the proof cylinder with the

45 type forms.

In the present construction the proof cylinder, as well also as the transfer cylinders, are not arranged to be raised and lowered relatively to the type forms and the printing

50 elements, but the proportions of the effective proof and transfer surfaces of said cylinders, with respect to the double bed, the printing forms, and the bed, which supports the printing element, as well also as the parts

55 of the machine intermediate and beyond said beds, is such as to always cause the clearance recesses of the cylinders to register with given transverse positions on the beds and frame, which may be termed striking positions.

Thus the front and rear ends and the

dividing rail of the double bed and the front and rear ends of the printing element bed may be denoted as striking positions for the cylinders, and the positive gear drive between the pinions 67 and racks 66 insures 70 permanency of register of the cylinders to make said striking positions effective. This is true whether the cylinders be rotated on their axes or not, for if a cylinder be moved without rotation from one striking position 75 to the other, at a time when the gear train is broken, establishment of said gear train will pick up the cylinder for properly striking the same as though the cylinder had been rotated when moving through the same 80 space.

When employing this construction and arrangement, it is desirable at times to allow the inking rolls to travel in contact with certain of the printing forms when the proof 85 cylinder is traveling in rolling contact therewith, and it is desirable at other times for the inking rolls to be lifted off of certain of the printing forms when the proof cylinder is traveling thereover, but not rotating in 90 proof contact therewith. I have herein shown a construction made as follows for so controlling the inking rolls as to effect these functions:

135 (Figures 9 and 11) designates a forwardly extending arm that can be fixed to or made integral with the triangular bearing plate 131. 136 designates a sleeve that constitutes the pivot of the demeshing lever 105 of the gear train for the proof cylinder. 100 Said sleeve 136 has rocking bearing in the plates of the cross head. It extends inwardly beyond the inner plate of the head. 139 designates a shaft that is rockingly mounted in the sleeve 136. It is provided at its outer 105 end with a hand lever 141 and at its inner end with a cam arm 142 that is adapted to bear on the lever arm 135.

With this construction, it will be observed that when the hand lever 141 is independently depressed, its crank arm 142 will depress the crank arm of the inking roll bearing plate 131 and raise the inking rolls above the level of the printing forms, and the parts can be locked with the inking rolls raised 115 by causing cam to pass dead center. When the cam is released the weight of the rolls causes them to descend to the level of the printing forms.

The rear end of the frame beyond the support for the printing element B is made of sufficient length to receive the transfer cylinder 57, when it is desired to transfer the impressions directly from the transfer cylinder 56 to said printing element B and to 125 also receive the transfer cylinder 56 when the latter is passed over the printing element. It is understood that the proportions of the effective transfer and printing surfaces of the transfer cylinders are such, rel- 130

atively to the travel of the cylinders along the frame to the printing element support as to bring the blanket of the transfer cylinder 56 into proper striking relation to the printing plate or element B. When the latter is brought directly back from the printing forms the said cylinder 56 can be locked as it leaves the rear side of the printing forms with its recess downwardly and may 10 be thus continued to a point in rear of the printing plate frame where return rotation thereof, when the cylinder 56 is adjusted to turn, will bring the striking parts on the printing element or plate and cylinder in 15 register, the imprinting from the cylinder 56 taking place on the return, turning movement of the cylinder. Thus the meshing of the pinion 67 with the racks can be relied upon to maintain the striking positions in 20 register. When, however, it is desired to reverse the lines picked up by the transfer cylinder 56, said cylinder will be rotated in peripheral contact with the cylinder 57 at the point indicated in Figure 2, and thereafter the cylinder 57 will be rolled towards 25 and over the plate or element B to transfer the impressions carried thereby to the printing plate or element. From the position shown in Figure 2 to the striking position 30 on the plate or element B, the angular travel of rotation of the roller 57 will be approximately 270 degrees. So also the length of the frame from the normal or inoperative position of the proof cylinder, as shown in 35 Figures 1, 3, and 4, will be such that said cylinder will travel about 270 degrees to bring its effective striking surface into striking position against the type forms.

In operation, assuming that the printing 40 forms are the up and down lines to produce a cross ruled sheet on the printing plate or element B, the down rule form and cross rule form are placed at the relative positions on the type form bed, as shown in Figure 1. 45 The down rule form is first proved and registered by running the proof cylinder and inking rollers therover. This form is located at the near left hand side of the printing form bed and becomes the key form. 50 Thereafter, the form is proved and registered with respect to the first proved form. It will be noted that the total length of the double bed is twice the effective proving surface of the proof cylinder; in other words, 55 the effective circumferential dimension of the proving surface equals slightly more than one half the length of the bed. The two parts of the bed, divided by the transverse rail, and the travel of the proof cylinder from the position shown in Figure 1, are such that substantially $1\frac{3}{4}$ revolutions of the proof cylinder will bring the clearance recess thereof at the lower side of the cylinder in line with said transverse rail. When proving the key form, the proof roller 60 may be advanced and turned on its axis to bring it to the latter position, and thereupon, its driving train may be disconnected and the lock pin 86 connected to the cylinder end, so that by reversing rotation of the crank 70 of the proof cylinder shaft the proof cylinder may be carried backwardly over the key form without rotation and without touching the key form. When the proof is found to be perfect and in register, the proof cylinder can again be caused to travel over the key form without rotation and to allow the inking rollers to be adjusted against the key form when the proof roller is returned. Thereafter, the transfer cylinder 56 can be 80 moved, bodily, forwardly over the printing form, it preferably being held from rotation until it reaches the striking position on the proof form at the exterior front margin thereof, and is thereafter locked and rotated 85 and picks up the impressions from the printing form and is then rolled backwardly away from the printing form bed. Thereafter, the second printing form 33' is in generally like manner proved and registered on 90 the rear part of the double bed. By reason of the fact that the proof cylinder will reach the striking surface of the second form, just after it has passed over the center rail, the impressions of the second form will be superimposed on the proof cylinder on the area occupied by the impressions of the key form on the proof cylinder. When it is found 95 that the lines of the object of the second form are in register with the lines of the 100 object of the key form, then the transfer cylinder 56 can be brought forward to pick up the impressions of the second printing form and superimpose them in proper relation 105 with the impressions of the key proof form theretofore transferred thereto. The two forms are now in perfect register, and the bed supporting the printing forms may be longitudinally and transversely adjusted 110 through the hand wheels 42 and 46 to separately collate the lines of the objects of the printing forms on different circumferential and longitudinal areas of the transfer cylinder until it is filled. Between such collating operations the proof cylinder will be run over 115 the forms in order to assure that the printing forms are in proper register and also to insure that the printing form surfaces are perfect in detail. The inking rolls will be adjusted to travel on the surfaces of the printing forms both ahead of the proof cylinder and ahead of each pass of the transfer cylinder. 120

If it be desired to use a third printing form having different object lines of the same color to be superimposed on the collated impressions of the first two forms, the second form will be removed from the bed and the third form will be substituted therefor, and the same proof and register opera- 125 130

- tions will be carried out with respect to the third, or any permissible number of, printing forms. In all these operations it will be understood that the proof and transfer cylinder will be moved over the bed out of contact with any particular portions of the printing forms which it is not desired to prove or pick up, respectively, this separation being effected by moving the cylinders bodily without turning them and with their clearance recesses faced downwardly. Alternatively, tracks may be employed for this separation by actively moving the rollers upwardly, as shown in my aforesaid patent. It will be noted that after the transfer cylinder 56 has been filled, the transfer therefrom, either to the second roller 57 or directly to the element B, can be effected in a single operation or complete travel of the roller the desired distance. When operating on printing forms of lesser dimensions the number of proving and transfer operations will be increased proportionate to the lesser sizes of the printing forms, but, in other respects, the operation will be identically the same.

If desired, the cross head frames for the cylinders 56 and 57 may be locked to the superframe by set nuts 155 or by other suitable means, in order that it will not be jarred out of place when the cylinder 56 is brought to the cylinder 57 for transferring operation. Furthermore the cross head for the cylinder 56 may carry a pointer 156 adapted to register with a register mark on one of the rails 64 when said cylinder reaches the outermost position, so that its surface will register with the striking position on the printing element or plate when the said cylinder is returned and is rotating.

In the foregoing described operation of superimposing impressions on the transfer roller, it is assumed that the impressions are for ink of the same color to produce a single collated impression on the printing form. If color plates are to be produced the objects of the printing forms are registered and proved on the bed 18 in the manner before described, but the impressions for plates of different colors will be separately picked and collated by the transfer cylinder and separately printed on the printing plates to produce color plates.

A press having a given effective circumferential length of transfer cylinder may be employed for preparing more than one size of offset or lithograph printing plates. This can be effected by the adjustable bed for the printing element B before described. After the impressions from one of the transfer cylinders fill the part of the plate between the frame rails the transversely adjustable bed can be moved, through the medium of the rack and screw mechanism described, under the supervision of a micrometer. Thus

the lengths of the printing plates can be increased two or more times to adapt them to offset or lithographic cylinders of different sizes.

In order to originally adjust the cylinders to the proper height, relatively to the printing forms and elements, the superframe may be adjustably connected to the main frame, as by means of the screws 152 threaded into lugged standards of the superframe and bearing on the main frame. These lifting and lowering screws may be associated with any suitable form of micrometer.

It is to be understood that variations in the structural details of the disclosed embodiment of my invention can be made without departure from the spirit and scope of the claims hereto appended and that it is the intent to claim all of inherent novelty herein disclosed.

I claim as my invention:

1. The method of producing printing elements, such as offset plates, lithograph plates, and the like, from printing forms which comprises the steps of proving and registering the forms on a support, rolling a cylindric transfer surface thereover to receive superimposed impressions from the forms, and finally transferring said superimposed impressions from the transfer surface to produce the desired plates.

2. The method described which comprises the steps of proving and registering two printing forms in a manner to produce a superimposed proof impression of said forms on a cylindric surface, and finally transferring the proved and registered forms to a printing plate.

3. The method described which comprises the steps of proving and registering two printing forms in a manner to produce a superimposed impression of said forms on a cylindric surface, relatively shifting said forms when so registered and collating the registered impressions to a transfer element.

4. The method described which comprises the steps of proving and registering two printing forms in a manner to produce a superimposed impression of said forms on the surface of a cylinder, relatively shifting said forms when so registered, collating the registered impressions on a transfer element, and reversing said impressions between the printing forms and said element, so that the impressions will appear reversed on the printing element relatively to said printing forms.

5. The method of producing printing elements, such as offset plates, lithograph plates, and the like, from printing forms which comprises the steps of proving and registering the forms on a support, rolling a cylindric transfer surface over and to receive superimposed impressions from the

forms, giving relative movement to said forms and said transfer surface to superimpose said impressions at different longitudinal and circumferential surfaces of the area 5 of the cylindric transfer surface, and imprinting the transferred impressions from said transfer surface to a printing plate.

6. The method of making plates from printing forms which comprises the steps of 10 proving and registering forms on a flat support, rolling a cylindric transfer surface thereover to receive impressions from said forms, with the forms spaced to place the objects of the forms in superimposed registered relation on the transfer surface, giving relative movement to the form support and the transfer surface to dispose said superimposed transfers longitudinally and circumferentially of the transfer surface, and 15 applying the transfer of said surface to a plate to produce the printing plate.

7. The method of making plates from printing forms which comprises the steps of proving and registering forms on a flat 20 support, rolling a cylindric transfer surface thereover to receive impressions from said forms, with the forms spaced to place the objects of the forms in superimposed registered relation on the transfer surface, 25 giving relative movement to the form support and the transfer surface to dispose said superimposed transfers longitudinally and circumferentially of the transfer surface, applying the transfer of said surface to a 30 plate to produce the printing plate, and transferring the impressions from said transfer surface to a secnd cylindric transfer surface to reverse the object impressions on a final printing plate.

40 8. The method of producing printing elements, such as offset, lithograph plates, and the like, from printing forms which comprises the steps of proving and registering the forms on a support, rolling a cylindric 45 transfer surface over and to receive impressions from the forms, imparting relative movement to said forms and said transfer surface to transfer said impressions at different longitudinal surfaces of the area of 50 the cylindric transfer surface, effecting relative separation of the effective area of the transfer surface and the printing forms, and imprinting the transferred impressions on the printing plate.

55 9. The method of making plates from proved and registered printing forms which comprises the steps of passing a rotary transfer surface in transfer contact with a form containing an object to be transferred, and 60 by continued rotation passing it in printing contact with a plate, and imparting relative movement of said transfer surface and of said form or plate to imprint the transfer on said plate in desired relative position on the printing plate.

10. The method of producing printing plates by the use of two transfer surfaces, which comprises the steps of directly transferring the object to one of said surfaces, transferring the object from the first to the 70 second transfer surface to reverse the object, and imprinting the reversed object on a printing plate.

11. The method of producing printing plates by the use of two rotary transfer 75 surfaces, which comprises the steps of rolling one of the surfaces over a printing form to receive a transfer, rolling the first surface peripherally against a second surface to reverse the object and afterwards rolling the 80 second transfer surface over a plate to imprint the reversed object directly thereon to produce the printing plate.

12. The method of making plates from 85 proved and registered printing forms which comprises the steps of passing a rotary transfer surface in transfer contact with a form containing an object to be transferred, reversing the lines of the object between the position from which it is taken from the form and the position at which it is imprinted on a printing element, and imparting relative movement of the transfer surface and of said form or plate to imprint the surface in a desired relation on the 90 printing plate.

13. The method of producing printing elements, such as offset plates, lithograph 100 plates, and the like, from printing forms, which comprises the steps of proving and registering the forms on a support, rolling a cylindric transfer surface over and to receive impressions from the forms, giving relative movement to said forms and said transfer surface to transfer said impressions at different longitudinal and circumferential surfaces of the area of the cylindric transfer surface, effecting relative separation of the effective area of the transfer surface and the printing forms and plate, and maintaining 105 the cylindric rolling surface in register with the printing forms and printing plate.

14. The method described which comprises the steps of first registering and proving a key form on a support, thereafter registering and proving another form through the guidance of said key form, and finally transferring the impressions from said forms to printing plates.

15. The method described which comprises the steps of first registering and proving a key form on a support, thereafter registering and proving another form through the guidance of said key form, imparting relative movement to the registered forms and the proving and registering medium, and transferring the impressions from said forms to printing plates.

16. The method described which comprises the steps of first registering and prov-

ing a key form on a support, thereafter registering and proving another form through the guidance of said key form, rolling a cylindric transfer surface over the registered forms to pick up impressions therefrom, imparting relative movement between the forms and transfer surface to transfer said impressions to different longitudinal and circumferential areas of the transfer

10 surface, and imprinting said transfer impressions on a plate.

17. A press for the purpose set forth comprising a frame, a printing form bed thereon, a transfer cylinder travelable over said bed to receive transfers from an object supported on the bed, a support for a printing plate over which the said transfer cylinder is adapted to roll to imprint the transfer impressions on a plate carried by the latter support, gear means on said cylinder and frame and wholly above the plane of a plate on said plate support to cause said cylinder to rotate and travel, and means to transversely adjust said plate support relatively to the transfer roller.

18. A press for the purpose set forth comprising a frame, a printing form bed thereon, a transfer cylinder travelable over said bed to receive transfers from an object supported on the bed, a support for a printing plate over which the said transfer cylinder is adapted to roll to imprint the transfer impressions on a plate supported on the latter bed, said plate support being disposed transversely of said frame and the printing form bed, gear driving means for said cylinder wholly above the plane of said support, and means to adjust the said plate support transversely with respect to said frame to enable printing plates of greater length than the transfer cylinder to be made by successive operations of the cylinder.

19. A press for the purpose set forth comprising a frame, a printing form bed thereon, a proof cylinder movable over said bed to prove printing forms thereon, a transfer cylinder travelable over said bed to receive transfers from an object supported on the bed, a support for a printing plate over which the said transfer cylinder is adapted to roll to imprint the transfer impressions on a plate supported on the latter bed, said support extending laterally from both sides of the frame to support a plural plate element, driving means for said cylinder wholly above the plane of a printing plate sustained on said support, and means to adjust said plate bed relatively to the transfer roller.

20. A press for the purpose set forth comprising a frame, a printing form bed thereon, a proof cylinder movable over said bed to prove printing forms thereon, means to adjust said bed relatively to said proof cylinder, a transfer cylinder travelable over

said bed to receive transfers from an object supported on the bed, internal driving gears within the end of said cylinder, and on said frame to cause rotation of said cylinder, a support for a printing plate over which the said transfer cylinder is adapted to roll to imprint the transfer impressions on a plate supported on the latter bed, and means to adjust said plate bed relatively to the transfer roller.

21. A proof and transfer press for making printing plates, such as offset and lithograph plates, comprising a frame, spaced printing form and printing element beds supported thereon, a proof cylinder travelable over the printing form bed, a transfer cylinder travelable over said printing form bed and over said printing element, top guided cross heads movable along guides on said frames in which said cylinders are mounted, racks extending longitudinally of said frame, and a train of gears for each cylinder carried by its cross head for connecting said racks to said cylinder to give traveling movement of the cylinder relatively to said frame.

22. A proof and transfer press for making printing plates, such as offset and lithograph plates, comprising a frame, spaced printing form and printing element bed supported thereon, a proof cylinder travelable over the printing form bed, a transfer cylinder travelable over said printing form bed and over said printing element, top guided cross heads movable along guides on said frame in which said cylinders are mounted, racks extending longitudinally of said frame, and a train of gears for each cylinder carried by its cross head for connecting said racks to said cylinder to give traveling movement of the cylinder relatively to said frame, said gear train being constructed to cause the cylinders to roll during travel and also to allow them to travel while non-rotative on their axes.

23. A proof and transfer press for making printing plates, such as offset and lithograph plates, comprising a frame, a spaced printing form and printing element bed supported thereon, a proof cylinder travelable over the printing form bed, a transfer cylinder travelable over said printing form bed and over said printing element, cross heads movable along guides on said frame in which said cylinders are mounted, racks extending longitudinally of said frame, and a train of gears for each cylinder carried by its cross head for connecting said racks to said cylinder to give traveling movement of the cylinder relatively to said frame, said gear trains having terminal pinions to mesh with said racks, and gears on the cylinder with which the other terminal pinions of the train mesh.

24. A proof and transfer press for mak-

- ing printing plates, such as offset and lithograph plates, comprising a frame, spaced printing form and printing element beds supported thereon, a proof cylinder travelable over the printing form bed, a transfer cylinder travelable over said printing form bed and over said printing element, cross heads movable along guides on said frame in which said cylinders are mounted, racks 10 extending longitudinally of said frame, and a train of gears for each cylinder carried by its cross head for connecting said racks to said cylinder to give traveling movement of the cylinder relatively to said frame, said 15 gear trains having terminal pinions to mesh with said racks, gears on the cylinder with which the other terminal pinions of the train mesh, and the gear trains each embracing a demeshing pinion to break the train from the rack to the cylinder gear.

25. A proof and transfer press comprising a frame, a printing form bed supported thereon, with means to prove and register printing forms on said bed, a transfer cylinder to receive impressions from the printing forms, an internal driving gear for said cylinder to cause it to rotate on its axis and to travel along said frame, a bed over which said cylinder rolls to support a plate wholly beneath said internal driving gear, which plate receives transfer impressions from said transfer cylinder, and means for adjusting the latter support laterally relatively to the frame. 30

In testimony whereof I claim the foregoing as my invention, I hereunto append my signature at Chicago, Illinois, this 3 day of August, 1921. 35

LOUIS SMITH.
